UNITED STATES PATENT OFFICE

124,607

DESIGN FOR A CLEARANCE LAMP FOR VEHICLES

Raymond F. Hutt, Fort Madison, Iowa, assignor
to Anthes Force Oiler Company, Fort Madison,
Iowa, a corporation of Iowa

Application September 25, 1940, Serial No. 95,353

Term of patent 7 years

To all whom it may concern:

Be it known that I, Raymond F. Hutt, a citizen
of the United States, residing at Fort Madison,
in the county of Lee and State of Iowa, have
invented a new, original, and ornamental Design
for a Clearance Lamp for Vehicles, of which the
following is a specification, reference being had
to the accompanying drawing, forming part
thereof.

Fig. 1 is a view in side elevation of a clearance
lamp for vehicles showing my new design;

Fig. 2 is a view in front elevation of the clear-
ance lamp for vehicles; and

Fig. 3 is a bottom plan view of the clearance
lamp for vehicles.

I claim:

The ornamental design for a clearance lamp
for vehicles, as shown.

RAYMOND F. HUTT,
